UNITED STATES PATENT OFFICE.

JACOB WEISSINGER, OF NEW YORK, N. Y.

LINOTYPE-MACHINE.

1,156,730.

Specification of Letters Patent.

Patented Oct. 12, 1915.

Application filed February 4, 1915. Serial No. 6,043.

To all whom it may concern:

Be it known that I, JACOB WEISSINGER, a citizen of the United States, and a resident of Glendale, in the city of New York, borough of Queens, county of Queens, and State of New York, have invented certain new and useful Improvements in Linotype-Machines, of which the following is a specification.

My invention relates to linotype machines, particularly to the matrices used therein, and the main object is to provide means for cleansing said matrices of dirt or corrosion automatically, whereby the characters therein are rendered clearly visible to the operator in the position of the first elevator.

A further object is to so construct the said cleansing means as to serve as a notification to the operator that a matrix is becoming worn out.

20 A further object is to cleanse the matrices just previous to their entry into the distributor box; and further objects are to provide such devices which are simple in construction, adapted for attachment to machines of the above class without any material alteration therein, positive in result, composed of few parts not likely to get out of order to require repair, and comparatively inexpensive.

30 My invention is fully described in the following specification, of which the accompanying drawings form a part, in which like reference characters refer to like parts in each of the views, and in which:—

35 Figure 1 is a fragmentary front view of a linotype machine in the position of the distributor box, and showing my invention in the present preferred position; Fig. 2 is an enlarged section taken on the line 2—2 of Fig. 1; and Fig. 3 is a fragmentary perspective view of a matrix.

40 In the drawings forming a part of this application I have shown the distributor arm 4 of a linotype machine with a plurality of matrices 5 being guided thereon on their way to the distributor box 6, said matrices being shown as on the second elevator 7 and adapted to be moved therefrom by means of the pusher 8, all of conventional 45 or any desired form.

50 My invention is shown as being mounted upon the front plate of the distributor box 6 and comprises a plate 9 detachably held on said box by means of a screw 10, a horizontal shaft 11 rotatable in said plate pro-

vided with a pinion 12 at one end and a bevel gear 13 intermediate its length enmeshed with a similar gear 14 carried by a vertical shaft 15 also rotatable in said plate, and provided with an abrasive disk or 60 brush 16.

The spur pinion 12 is enmeshed with a similar pinion 17 mounted on a shaft 18 connected with the lower, front, distributor screw of the machine, and it will be seen 65 that the disk or brush 16 is revolved in the rotation of said screw. I provide a slot 20 in the front plate of the box 6, as clearly shown in Fig. 2, to allow the disk or brush 16 to extend into said box and in the path 70 of forward movement of the matrices toward their magazines, this slot and disk being in the position of the characters in the matrices, whereby said matrices are polished in the positions of the characters therein in 75 their passage past the disk 16, thus rendering the characters clearly visible.

The matrices are normally held against any appreciable movement laterally of said box while passing therethrough but, when 80 they become worn, an appreciable movement is possible; this movement of the worn matrices allows them to yield to the pressure of the disk 16 and the matrices are not, therefore, cleansed by said disk, whereas all 85 the matrices not so worn are thoroughly cleansed by the disk. When the matrices are again carried into first elevator position the characters on the matrices not worn are clearly visible, but the characters on the 90 worn matrices are not so clearly visible, with the result that the operator is thus acquainted with the matrices which are worn and need to be replaced.

95 My device is intended to clean the matrices in the positions of the reference characters thereon after they have been separated from the space-bands and without taking the matrices from the machine; the reason for this is that on all machines using 100 space-bands the latter need to be cleaned with graphite every eight hours that the machine is in use; on linotype machines the matrices and space-bands must travel together until they reach the transfer point 105 where the space-bands are left and the matrices pass to the distributor box; by the matrices and space-bands traveling together the graphite with which the space-bands have been cleaned covers up the reference char- 110

acters so as to render it impossible for the operator to distinguish the same while the matrices are in the assembler.

On all linotype machines using matrices, 5 the latter travel into the distributor box with the reference characters thereon facing the front of the machine, the casting face or molds facing toward the rear of the machine, as the matrices will not travel through 10 distributor box otherwise, and it is because of this that I slot the front plate and mount my device thereat.

The point of operative connection with the machine, to the lower, front, distributor 15 screw, forms an essential feature of my device inasmuch as the distributor box on all linotype machines needs to be taken off when a matrix gets caught therein, said distributor box being moved downward for 20 separation from the machine. This requires that I shall have the pinion 12 beneath the distributor screw pinion 17, otherwise I would have to remove my device from the distributor box before it could be removed 25 from the machine.

The important points of my invention are that cleaning takes place on the fronts of the matrices, after the space-bands with their adhering graphite have been separated 30 therefrom, before the matrices enter the magazine; the connection of my device with the lower, front, distributor screw; the removal of my device with the distributor box; and the unit formation of my device 35 enabling the same to be readily assembled on machines already in use.

Having fully described my invention, what I claim as new, and desire to secure by Letters Patent, is:—

40 1. The combination with a linotype machine provided with a plurality of matrices

having reference characters thereon, a detachable distributor box, and a lower, front, distributor screw; of an abrasive element, in the path of said matrices to be distributed, 45 projected through the front plate of and portable with said box, and means for operatively connecting said element with said lower, front, distributor screw.

2. The combination with a linotype machine provided with a plurality of matrices having reference characters thereon, a detachable distributor box, and a lower, front, distributor screw; of a disk projected through the front plate of and portable with 50 said box in the path of the characters on said matrices, and means for operatively and detachably connecting said element with said lower, front, distributor screw.

3. The combination with a linotype machine provided with a plurality of matrices having reference characters thereon, a detachable distributor box, and a lower, front, distributor screw; of a plate secured to the front of said box, a shaft carried by said 65 plate, a disk revoluble with said shaft, a pinion on said shaft, a supplemental shaft geared to said pinion, and gears connecting said supplemental shaft and said lower, front, distributor screw, the front of said 70 box being slotted to receive said disk and permit the same to bear on said matrices in the positions of said characters in the movement of said matrices to be distributed.

In testimony whereof I have signed my 75 name to this specification in the presence of two subscribing witnesses.

JACOB WEISSINGER.
